UNITED STATES PATENT OFFICE.

EZRA CAMPBELL, OF DAYTON, WASHINGTON.

GRIPPER FOR JOB-PRINTING PRESSES.

SPECIFICATION forming part of Letters Patent No. 588,895, dated August 24, 1897.

Application filed May 25, 1896. Serial No. 592,976. (No model.)

To all whom it may concern:

Be it known that I, EZRA CAMPBELL, a citizen of the United States, residing at Dayton, in the county of Columbia and State of Washington, have invented certain new and useful Improvements in Job-Printing Presses; and I do hereby declare the following to be a full, clear, and exact description of the invention, such as will enable others skilled in the art to 10 which it appertains to make and use the same.

My invention relates to grippers used in "job-printing" presses for holding the paper in position while being printed.

My object is to provide improved and simple mechanism for easily and quickly adjusting the spring gripping-fingers, so that provision can be made for accommodating different widths of paper.

Having this object in view, the invention 20 consists of certain novel features and combinations, as will appear more fully hereinafter.

In the accompanying drawings, Figure 1 is a side elevation of my complete invention; Fig. 2, a longitudinal section taken on line 25 xx of the preceding figure; and Fig. 3, a detail view of the spring-bracket and shaft passing through the same, full lines representing the bracket in engagement with the shaft and dotted lines out of engagement therewith.

30 A represents the frame, to which the spring-grippers are connected. This frame is provided with ears 1 for connection to the printing-press. The frame is also provided with two aligned guide-slots 2 and 3, which are separated by a cross-piece 4. Additional narrow guide-slots 5 and 6 communicate with the aforesaid slots.

The spring gripping-fingers 7 and 8 are connected at their lower ends to the necks 9 and 40 10 of respective internally-screw-threaded nuts 11 and 12. The necks travel in the slots 5 and 6 and the nuts in the slots 2 and 3, so that the gripping-fingers slide against the face of the frame, as shown.

45 I employ two long screws 13 and 14, provided with right and left hand screw-threads, respectively. The screw 14 passes through the nut 11, being in engagement with the screw-threads thereof. This screw is journaled in

the frame at 15 and 16, respectively, the journal 16 being cut away at 17 to provide a clutch member. The screw 13 is provided with journals 18 and 19, the former of which is provided with a clutch member 20, adapted for engagement with clutch member 17, and is 50 movable in the journal-bearings in the frame. The other end of the screw is extended into an enlarged spindle 21, which is provided with two peripheral notches 22 and 23 and carries a hand-wheel 24 on its extremity. 55

A spring-bracket 25, fastened to the frame by a screw 26, is adapted for engagement with the notches 22 and 23 to hold the spindle and screw in locked position. I also provide a suitable dust-cap 27, a screw 28 for 60 fastening it to the frame, and oil-holes 29.

The operation is as follows: Should it be desired to shift the spring-finger 8, the spring-bracket will be in engagement with notch 22, and if the hand-wheel is turned the screw 13 70 is rotated. The direction of rotation of the screw will determine whether this spring-finger is advanced or retreated. If, however, it is necessary that both fingers be adjusted simultaneously, the spring-bracket is depressed and the spindle and screw slid inwardly. The bracket will then spring into notch 23 and the clutch members be thrown into engagement. If the hand-wheel be rotated in one direction, the spring-fingers will 75 advance simultaneously, and if rotated in the opposite direction they will retreat. Adjustment of the spring-fingers may thus be easily and quickly effected, so that different widths of paper can be accommodated. 80

It is to be understood that I do not limit myself to the precise construction herein shown and described, but consider myself entitled to all such variations as come within the spirit and scope of the invention. 85

Having thus described the invention, what is claimed as new is— 90

In a paper-gripper for printing-presses, the combination with a frame, of separate screws journaled in said frame having oppositely-inclined screw-threads, both of said screws carrying clutch members, and one of the screws being adapted for longitudinal move- 95

ment whereby the clutch members can be thrown either into or out of engagement, a catch adapted to connect with the movable screw, and gripping-fingers, one being operated by one screw and the other by the other screw.

In testimony whereof I have signed this

specification in the presence of two subscribing witnesses.

EZRA CAMPBELL.
